UNITED STATES PATENT OFFICE.

JAY DARLING, OF WILLIAMSPORT, INDIANA.

WIRE-BENDING MACHINE.

1,388,409.

Specification of Letters Patent. Patented Aug. 23, 1921.

Application filed September 9, 1920. Serial No. 409,223.

To all whom it may concern:

Be it known that I, JAY DARLING, a citizen of the United States, residing at Williamsport, in the county of Warren and State of Indiana, have invented a new and useful 5 Wire-Bending Machine, of which the following is a specification.

The object of my invention is to provide an implement adapted to form a wire fastener of the novel form illustrated for use in the construction of wire fences, the fasteners being partially embedded in concrete posts. I attain the objects of my invention by the mechanism illustrated in the accompanying 15 drawings, in which—

Figure 1 is a plan view of my invention, with the wire bending arms shown in their initial position before the wire is cut or bent;

Fig. 2 is an elevational view with the lever 20 13 in position for the third operation, as indicated at C;

Fig. 3 is a similar elevation with the lever 21 in position E following the final operation of bending the wire fastener;

Fig. 4 is a top plan or edge view;

Fig. 5 is a side elevation looking from the side of lever 10 with parts shown as in Fig. 2;

Fig. 6 is a side elevation from the opposite side of Fig. 2;

Fig. 7 is a transverse section on the line 7—7 of Fig. 2, showing the parts in the position shown in full lines in that figure;

Fig. 8 is a section on the line 7—7 of Fig. 2, showing the parts in position shown in dotted lines in Fig. 2;

Fig. 9 is a perspective view of the head of lever 13; and

Fig. 10 is a perspective view of the completed wire fastener.

Like numerals designate like parts in each of the several views.

Referring to the accompanying drawings I provide a base-plate 1 suitably mounted, 45 as by screws 2, on a suitable rigid support. Member 1 is provided with an upstanding lug 3, on either side of which are pivotally mounted levers 10 and 13, the respective heads 12 and 15 of which are pivoted to plate 1 by the respective pivots 11 and 14. Spaced from lug 3, approximately the length of the wire fastener W, I provide a bending anvil 4 having a raised extension 5 suitably affixed to member 4 as by screws 6. 50 Positioned between lug 3 and bending anvil 4, in spaced relation to said members, I pro-

vide a vertically extending bending anvil 7 having a longitudinal upstanding flange 8.

Bending anvil 4 is provided with a lateral extension 9 over which the head 22 of the 60 third bending lever 21 operates. Lever 21 is pivotally mounted on bending anvil 4 by a suitable pivot 25.

I provide an extension plate 16 suitably affixed, as by screws 17, to head 15 of the 65 second bending lever 13, as shown in Fig. 2.

Extension plate 16 is provided with a transverse undercut groove 18, as shown in Fig. 9.

Extension 5 of bending anvil 4 is provided 70 with a horizontally projecting bending anvil 19, there being a recess 20 between said anvil 19 and the base-plate 1.

Near the edge of base plate 1 I provide a 75 wire-cutting flange 23, positioned to operate with the undercut groove 24 in the head 12 of lever 10.

To operate the device the levers 10 and 13 are first moved to the position shown in Fig. 80 1 and a straight strip of wire W is placed on the plate 1 between lug 3 and the adjacent end of the vertical bending anvil 7. The first bending lever 10 is then moved to the position A, making the initial bend in the wire.

The next step in the operation of producing the fastener is to move the second bending lever 13 from the position shown in full line in Fig. 1 to position B in that figure. Lever 13 is then moved back to its former position, designated C in Fig. 2, and 90 the projecting end of wire W is bent reversely manually and the lever 13 is thereupon swung to position D, causing the wire to bend around the rounded end of the horizontally projecting anvil 19, as shown in Fig. 8. The third bending lever 21 is thereupon swung from the position shown in Fig. 2 to a position at right angles thereto, designated E in Fig. 3, producing the final bend in the wire fastener. 95

When the wire W is first placed on the bending plate it is severed to the required length by swinging lever 10 over the wire-cutting flange 23 on the edge of the base-plate, the grooved head 12 of lever 10 operating with flange 23 to sever the wire. 105

What I claim is:

1. In a wire bending device of the class described, the combination of a base-plate, spaced upstanding lugs and bending anvils 110 of suitable shape and positioning to give the wire the desired form while being bent,

spaced bending levers pivotally mounted on the base-plate and having enlarged heads shaped to bend the wire in the required shape, and a third bending lever pivotally mounted substantially midway between the first mentioned bending lever and having a laterally extending head adapted to effect the required final bend in the wire, whereby a plurality of bends are made to complete a 10 wire fastener of the shape shown.

2. In a device of the class described the combination of a base-plate, an upstanding lug, a longitudinal upstanding flange spaced from said lug, a bending anvil spaced from 15 the other end of the longitudinal upstanding flange, said bending anvil having a horizontally projecting extension, and a plurality of spaced bending levers pivotally mounted and suitably shaped and positioned to operate with the above described anvil and flange to bend a wire fastener to the shape shown.

3. In combination with the mechanism described in claim 2 one of the bending levers mentioned having a groove, and a wire-cut-

ting flange mounted on the base-plate near 25 one edge thereof in position to operate with said bending lever to sever the wire to the desired or required length.

4. In a device of the class described, a base-plate, means for holding a wire in position while being bent, a pivotally mounted bending lever for first making a right-angle bend in the wire, a second bending lever pivotally mounted on the base-plate and shaped and positioned to bend the wire to a 30 transversely extending parallel position, said bending lever having a grooved extension element adapted to engage and bend the wire in a transverse direction, and a third and pivotally mounted bending lever adapted to 35 engage the transversely bent wire and bend same in a direction at right angles to said transverse bend and longitudinally and parallel with the longitudinally extending parts of the wire, for producing a wire fastener of 40 45 the shape shown.

JAY DARLING.
